PHILIPPE AUGUSTE GUYE, OF GENEVA, SWITZERLAND.

PROCESS FOR THE RECOVERY OF NITROGEN OXIDS.

1,331,104.

Specification of Letters Patent. Patented Feb. 17, 1920.

Application filed January 4, 1919. Serial No. 269,727.

To all whom it may concern:

Be it known that I, PHILIPPE AUGUSTE GUYE, a citizen of Switzerland, residing at Geneva, Switzerland, have invented new and useful Improvements in Processes for the Recovery of Nitrogen Oxids, of which the following is a specification:

This invention relates to a novel and useful process of recovering nitrogen oxids, 10 and particularly such as are produced by subjecting a dry mixture of nitrogen and oxygen to the action of an electric arc.

As is well known, when a gaseous current consisting of a dry mixture of nitrogen and oxygen, either in the proportions of atmospheric air or any other proportions, is subjected to the action of an electric arc, there is produced nitric oxide, (NO) which passing out with the gaseous current is trans- 20 formed by cooling into nitrous anhydrid (N_2O_3) and into nitrogen peroxid (N_2O_4), or NO_2 . These substances constitute what are generally termed nitrous oxids. In the presence of an excess of oxygen, and within 25 a short period of time, in some instances from one to three minutes, the oxidation is nearly complete and the nitrous oxids are composed almost exclusively of peroxid of nitrogen.

Heretofore attempts have been made to recover this peroxid of nitrogen by cooling the gaseous mixture, but such a method has been found unsatisfactory because of certain inherent difficulties, for instance, the per- 35 oxid of nitrogen being heavily diluted with air (generally in the order of 1% in volume) its liquefaction cannot be completed except by reducing the temperature of the whole gaseous mass to -80 degrees C. (more 40 or less). Since peroxid of nitrogen solidifies at +7 degrees C. the result is that the condensing coils of the apparatus commonly employed in carrying out this ordinary method of recovery are rapidly covered with 45 solid peroxid of nitrogen, which obstructs the coils and diminishes the efficiency of the apparatus. To avoid this disadvantage it has been proposed to use two condensing apparatuses working alternately, one being 50 employed for condensation while the other is used in order to re-liquefy by heat the solidified peroxid of nitrogen. It has been the practice to introduce into the condensing coils a liquid which will not be attacked 55 by the peroxid of nitrogen, and which liquid

will form with such peroxid of nitrogen a mixture non-congealable at a low tempera- 60 ture. For instance, carbon tetrachlorid has been employed for this purpose, and from the resulting mixture the peroxid of nitrogen is recovered by fractional distillation.

It will therefore be noted that such methods or processes of recovering nitrogen oxids are complicated, tedious and expensive. 65

The purpose of the present invention is to obviate the above recited disadvantages by providing a simple, economical and efficient process for recovering these oxids.

In the practice of my invention I accom- 70 plish this purpose by regulating the time for the oxidation of the nitrogen peroxid gas after its formation in the electric arc, in such manner that the moment the gases reach the condenser the nitrous oxids, com- 75 posed of peroxid of nitrogen in the presence of a certain quantity of nitrous anhydrid sufficient for the mixture of both compounds, remain liquid at the determined tempera- 80 ture of liquefaction, that is, -80 degrees C., as heretofore mentioned.

The pure nitrous anhydrid remaining liquid below -100 degrees C., and easily dissolving in every proportion the peroxid of nitrogen, a relatively small proportion 85 of nitrous anhydrid is sufficient to obtain the desired result. As a convenient proportion, we may resort to that which corresponds to about equal parts of the two substances, and with even smaller quantities of 90 nitrous anhydrid the mixture will remain liquid at less than 0 degrees C.

If the oxidation of the nitric oxide (NO) has been satisfactorily regulated to this condition, the liquefaction of the nitrous oxids 95 may be effected continuously and in the same apparatus, without the deposit of solid peroxid of nitrogen and without obstructing the coils of the apparatus, and furthermore, the necessity of following the practice of 100 employing a solvent which will not solidify and then separation by fractional distillation is avoided. So far as concerns the nitrous oxids (the mixture of nitrous anhydrid and nitrogen peroxid) liquefied and 105 collected in the condenser, it is sufficient to treat the same with oxygen in order to effect a total transformation of these oxids into peroxid of nitrogen, or else to transform 110 them into nitrous anhydrid with nitric oxid

(NO), or to transform them into concentrated nitric acid with water and oxygen under pressure.

- 5 It is to be noted that in order to obtain 5 nitrous anhydrid (for the manufacture of 10 nitrites, for instance) the time for the oxidation of the nitric oxide gas (NO) should be regulated so as to obtain the largest 15 quantity possible of nitrous anhydrid by 20 condensation, in this case the period or duration of oxidation being diminished. The 25 opposite course should be taken when it is desired to obtain peroxid of nitrogen in the main.
- 15 In order to regulate the time for the oxidation of the nitric oxid, as mentioned, a simple apparatus, such as is shown in the drawing may be employed. This comprises an oxidizing chamber A divided by partitions 20 into a selected number of compartments shown at 1—2—3 and 4. The gas enters through the main line inlet 5 and leaves through the outlet 6, so far as concerns its travel with relation to these compartments.
- 25 Suitable valves, shown at 7, 8, 9 and 10 are employed for the purpose of putting any compartment or compartments out of communication with the gas main, as may be desirable. The compartments are arranged 30 in such manner as to facilitate introduction or removal of the gases; to regulate the composition of the gaseous mixture of nitrogen and oxygen according to the temperature of the gases, especially to obtain 35 nitrous anhydrid, or, on the other hand, to obtain nitrogen peroxid, and finally by determining the power absorbed by the arc furnaces, to vary between wide limits the capacity of the oxidizing chamber.
- 40 The cooling of the gases may be accomplished in any preferred manner, as for instance, by the circulation of the gases in a suitable coil 11 externally cooled either by 45 a constantly circulating bath of cool liquid, such as toluene or petroleum, or by cool air, or by any other means. The cooling may also be accomplished by compression of from three to five atmospheres followed by 50 the expansion of the gaseous mixture containing the nitrous oxids.

What I claim is:

1. In the process of recovering oxids of nitrogen from a mixture thereof with other gases by oxidizing the oxids and subsequently liquefying them by refrigeration, the step which consists in regulating the oxidation of said oxids so as to produce a mixture of oxids of nitrogen which will not solidify above zero degrees centigrade.
- 60 2. In the process of recovering oxids of nitrogen from a mixture thereof with other gases by oxidizing the oxids and subsequently liquefying them by refrigeration, the step which consists in regulating the 65 oxidation of said oxids to produce a mixture

of nitrous anhydrid and peroxid of nitrogen which will not solidify above zero degrees centigrade.

3. In the process of recovering oxids of nitrogen from a mixture thereof with other 70 gases by oxidizing the oxids and subsequently liquefying them by refrigeration, the steps which consist in oxidizing the oxids by passing them through an oxygen-containing chamber and in varying the size 75 of said chamber to vary the extent of oxidation, so as to produce a mixture of different oxids which will not solidify above zero degrees centigrade.

4. In the process of recovering oxids of 80 nitrogen from a mixture thereof with other gases by oxidizing the oxids and subsequently liquefying them by refrigeration, the steps which consist in providing a plurality of oxygen-containing compartments, 85 and passing the oxids through a selected number of said compartments in succession, the number of compartments used being determined by the extent of oxidation desired, so that the gases passing to the refrigerating means will contain a mixture 90 of oxids of nitrogen which will not solidify above zero degrees centigrade.

5. In the process of recovering oxids of 95 nitrogen from a mixture thereof with other gases by oxidizing the oxids and subsequently liquefying them by refrigeration, the steps which consist in providing a plurality of oxygen-containing compartments, and passing the oxids through a selected 100 number of said compartments in succession, the number of compartments used being determined by the extent of oxidation desired, so that the gases passing to the refrigerating means will contain a mixture of 105 peroxid of nitrogen with nitrous anhydrid, which will not solidify above zero degrees centigrade.

6. The herein described process for the transformation of a variety of oxids of nitrogen, mixed with other gases, into a single 110 oxid of nitrogen, which includes, first, the partial oxidizing of said oxids so as to produce a mixture of nitrogen oxids including peroxid of nitrogen and sufficient nitrous 115 anhydrid to prevent said peroxid from solidifying at temperatures above zero degrees centigrade; next cooling the mixture to liquefy said oxids without liquefying the remaining gases; then segregating the liquefied oxids, and finally, chemically treating said oxids to vary the amount of oxygen in the molecules of all but one of said oxids to reduce them to the same chemical character as the unchanged oxid, producing a 120 single oxid as the product.

In testimony whereof I have hereunto set my hand.
